UNITED STATES PATENT OFFICE.

EVERETT R. BURTNETT, OF LOS ANGELES, CALIFORNIA, ASSIGNOR, BY DIRECT AND MESNE ASSIGNMENTS, TO THE AUTOMOTIVE VALVES CO., OF LOS ANGELES, CALIFORNIA, A VOLUNTARY TRUST.

INTERNAL-COMBUSTION ENGINE.

Application filed August 13, 1923. Serial No. 657,239.

My invention relates to an air cooled, two stroke cycle internal combustion engine and the principal objects of my invention are, to provide a two stroke cycle internal combustion engine having but two cylinders, two pistons and two cranks on the crank shaft, said parts being arranged so as to develop a power impulse, each 180 degrees of the crank shaft rotation, said engine having a valved port adapted to release the hot burnt gases or products of combustion in front of the engine structure, directly in the path of an air cooling draft; to provide an engine having a charge stratification and ignition chamber; to provide an engine in which the flames of combustion will be prevented from reaching the piston by the constant retention of the full cylinder displacement of spent products of combustion and in which engine additional piston cooling is effected to the combustion chamber piston by the pumping of the gaseous fuel mixture into an annular chamber that surrounds the lower structure of said piston.

A further object of my invention is the provision of an engine of extreme simplicity and rugged structure with parts constructed, arranged and timed for increased operating efficiency, cooling efficiency, thermal efficiency, and of minimum cost of production, operation and maintenance.

With the foregoing and other objects in view, my invention consists in the combination of a two diameter cylinder in which a two diameter piston is arranged for operation, thereby providing two piston chambers, one of cylindrical form between the center cylinder head and the inner piston head, the second, an annular formed chamber between the first and second diameters of the cylinder and piston; the inner or cylindrical chamber having a side pocket to the compression clearance, said side pocket having two ports, valvular means for said ports, an ignition device in the pocket; one port in the side pocket being for the release of the spent products of combustion, the second port to said pocket being for the admission of precompressed gaseous fuel mixture as a supercharge to the chamber of which the pocket is a part; a pocket to the annular chamber and a port to said pocket,

valvular means for said port, the latter being for the admission of a gaseous mixture to the said annular chamber as a displacement to the piston stroke; a crank shaft having one crank throw for each two diameter cylinder, a connection between the said crank and the two diameter pistons, valve actuating means directly applied to the crank shaft, for the operation of the two valves in the pocket of the first chamber, and for operating the valve in the pocket of the annular or second chamber, the arrangement of the cylinder and the first chamber pocket so that the port and the valve functioning for the release of the hot spent products of combustion, are located of the engine, on a line parallel with the axis of the crank shaft; a pair of two diameter, two chamber cylinders, disposed in V-arrangement, and radial relative to the axis of the crank shaft, the cylinders in structure being identical and each located so that the port and valve in the pocket that controls the release of the spent hot products of combustion, are formed on a line parallel with the axis of the crank shaft and said engine having conduits arranged between the annular chamber of each cylinder and the valved port of the pocket of the cylinder head chamber adapted for the admission of pre-compressed gaseous mixture as a supercharge to the residual volume content of the cylindrical chamber and pocket of the other cylinder.

Fig. 1 is a vertical section taken transversely of the engine and through the centers of the cylinders thereof.

Fig. 2 is a vertical longitudinal section taken through the center of one of the engine cylinders and through the center of the crank case.

Referring by numerals to the accompanying drawings, 10 designates a suitably formed crank case, having bearings 11, preferably of the ball or roller type, for a crank shaft 12, which latter is provided with two cranks 13 and 14 that are disposed less than 180 degrees apart.

Positioned on top of the crank case in V-arrangement and on opposite sides of the vertical center line of the engine are cylinders 15 and 16, the same being offset

slightly relative to each other lengthwise of the crank shaft so that their axes are in alignment respectively with the cranks 13 and 14.

5 These cylinders are preferably arranged so that their axes intersect the axis of the crank shaft and in order that the pistons that operate within said cylinders may function properly, the number of degrees between the axes of said cylinders is substantially equal to the number of degrees between the axes of the cranks 13 and 14 and points 180 degrees apart in the throw or circular path of travel of said cranks. For 10 instance, if the axes of the cylinders are disposed 60 degrees apart, then the cranks are arranged 120 degrees apart or 60 degrees less than 180 degrees.

The cylinders 15 and 16 are practically 20 identical in size, form and construction and each having a two diameter bore, with the bore or chamber 17 of smaller diameter in the upper portion of the cylinder block and the bore or chamber 18 of larger diameter 25 in the lower portion of said block.

Arranged for reciprocatory movement with each cylinder is a two diameter piston 19, the main body portion of which, or the portion having the smaller diameter, operates within the chamber 17 and the lower portion 20 of said piston or the portion having the larger diameter being arranged for operation within the larger chamber 18 in the cylinder.

35 A connecting rod 21 connects the piston in cylinder 15, with crank 13 and a similar rod 22 connects the piston in cylinder 16 with crank 14.

Formed integral with or fixed to the rear 40 portion of each cylinder 15 and 16, is a tubular fitting 23, the inner end of which communicates with the upper portion of the chamber 18 of larger diameter within the cylinder and formed within said fitting intermediate its ends is a seat upon which normally rests a spring held valve 24.

The lower end of the depending stem of 50 this valve is engaged by the upper end of a plunger 25 that is arranged for sliding movement in a suitable bearing 26, in the upper portion of the crank case 10 and the lower end of said plunger bears on the periphery of a cam 27, that is secured to crank shaft 12.

55 The outer end of the duct through fitting 23 is connected to a suitable source of gaseous fuel supply, preferably a carburetor.

Each cylinder is formed at its upper end 60 with a short forwardly projecting housing 28 in the outer portion of which is formed an ignition chamber 29 and the latter being connected to the upper end of chamber 17 by a short goose-neck duct 30.

Leading downwardly from the ignition 65 chamber 29 is an exhaust duct 31 and nor-

mally resting upon a seat that is formed between said chamber 29 and duct 31 is a spring held exhaust valve 32.

The lower end of the depending stem of this exhaust valve engages the upper end of 70 a plunger 33 and the lower end of the latter bears on the periphery of a cam 34, that is secured to the crank shaft.

Seated in the wall of housing 28 that surrounds the ignition chamber 29 is a spark 75 plug 35, the inner ends of the electrodes thereof terminating within said chamber.

Seated in the upper portion of housing 28 above the ignition chamber 29 is a valve cage 36, having at its lower end, a seat for a 80 spring held gaseous fuel inlet valve 37.

Bearing on the upper end of the stem of this valve is the inner end of a rocker arm 38, that is fulcrumed on a bracket 39 and bearing against the under side of the outer 85 end of this arm is the upper end of a push rod 40.

The lower end of this push rod bears on the upper end of a plunger 41 that is arranged to slide through a suitable bearing 90 42 and the lower end of said plunger bearing on a cam 43 that is secured to the crank shaft.

Inasmuch as there are two cylinders in my improved engine, it necessarily follows 95 that there are two compressed gaseous fuel transfer valves 37 and their actuating cams 43, two exhaust valves 32 and their actuating cams 34 and two gaseous fuel inlet valves 24 and their actuating cams 27.

The upper portions of the cylinders 15 and 16 and their extensions 28 are formed with externally arranged heat radiating fins 44 and arranged for operation on a bracket 45 that projects from the front end of the crank case, is a fan or fans 46 that may be driven in any suitable manner and which are adapted to direct blasts of cooling air rearwardly over the housings 28 and upper portions of the cylinders.

Formed through the wall of each cylinder at the upper end of the larger chamber 18 therein is a port 47 and leading therefrom to an inlet port 48 that is formed in the valve cage 36, in the upper end of the other cylinder is a compressed gaseous fuel transfer duct 49.

Thus, gaseous fuel that is compressed within chamber 18 in cylinder 15 is transferred to the ignition and combustion chambers at the upper end of cylinder 16 and vice versa.

The operation of my improved engine is as follows:

At the point of highest compression, or as the piston passes high center at the inner end of its stroke, a spark is produced between the terminals of the electrodes of the corresponding spark plug, thus igniting the charge of compressed gaseous fuel within 125 130

the corresponding ignition chamber 29 and the force of the expansion following combustion will act against the head of the corresponding piston to drive same downward 5 on its power stroke.

As the piston approaches and passes low center, the corresponding cam 34 actuates its plunger 33 to lift exhaust valve 32 from its set, thereby bringing about an instantaneous reduction in pressure and permitting a substantial portion of the products of combustion to exhaust past the open valve 32 and out through duct 31.

The exhaust valve then closes and practically at the same instant the fuel transfer inlet valve 37 is opened as a result of the corresponding cam 43, actuating plunger 41, push rod 40 and rocker arm 38 and as said valve is opened, a charge of precompressed 20 gaseous fuel is admitted to ignition chamber 29, duct 30 and to the upper portion of the piston sweep chamber 17 above the stratum of residual products of combustion therein.

It will be understood that this admitted 25 charge of gaseous fuel was compressed in the compression chamber 18 of the other or opposite cylinder, during the upward or inward movement of the piston therein, particularly the lower portion 20 of larger 30 diameter and that the compressed fuel passes through the corresponding transfer duct 49, into and through the corresponding inlet port 48.

It will also be understood that owing to 35 the arrangement of the cranks 13 and 14, the pistons travel in opposite directions, so that when the piston cylinder 16 is at the lower or outer end of its stroke, the piston in cylinder 15 is at the upper or inner end of its 40 stroke.

After the transfer inlet valve 37 closes, the continued upward movement of the piston will compress the admitted charge of gaseous fuel within the chamber 29 and the volume 45 of residual products of combustion will be compressed in a stratum in chamber 30 and in that portion of the chamber 17, above the piston.

Thus, the charge of gaseous fuel and residual products of combustion are compressed 50 in stratified relation and the expansive forces of the fuel charge when ignited and burned, act through the compressed non-combustible volume against the head of the piston to drive same downward on its power stroke.

Obviously the disposition of a stratum of residual products of combustion directly 55 above the piston, tends to counteract the excessively high temperatures that would otherwise pass from the burning charge to the head of the piston and this cooling effect is enhanced by the flow of relatively cool 60 products of combustion into the annular compression chamber 19 around the lower portion of the piston.

The upper portions of the cylinders and the housings 28 are cooled by the blasts of air directed against the fins 44 and this action is enhanced by the flow of comparatively cool compressed products of combustion through the inlet valve cage, into the chamber 29 and against the adjacent exhaust valve.

Thus it will be seen that I have provided a relatively simple and practical two stroke 75 cycle, two cylinder internal combustion engine that may be economically employed wherever rotary motion and power are desired.

It will be understood that minor changes 80 in the size, form and construction of the various parts of my improved engine may be made and substituted for those herein shown without departing from the spirit of my invention, the scope of which is set forth in 85 the appended claims.

I claim as my invention:

1. In an internal combustion engine, a pair of cylinders, each having a two diameter bore, the head portion of the smaller bore 90 of each cylinder having a lateral pocket, a pair of ports in each pocket, a valve controlled gaseous fuel inlet port communicating with the upper portion of the larger bore 95 in each cylinder mechanically actuated valves normally closing all of said ports, and means including cams mounted directly on the crank shaft of the engine for unseating all of said valves.

2. In an internal combustion engine, a 100 pair of cylinders, each having a two diameter bore, the head portion of the smaller bore of each cylinder having a lateral pocket, a pair of ports in each pocket, a gaseous fuel inlet port communicating with the upper 105 portion of the larger bore in each cylinder, a duct leading from the upper portion of the larger bore in each cylinder to the pocket at the head end of the other cylinder mechanically actuated valves normally closing 110 all of said ports, and means including cams mounted directly on the crank shaft of the engine for unseating all of said valves.

3. In an internal combustion engine, a 115 pair of cylinders, each having a two diameter bore, the head portion of the smaller bore of each cylinder having a lateral pocket, a pair of ports in each pocket, a gaseous fuel inlet port communicating with the upper portion of the larger bore in each cylinder, a two diameter piston arranged for operation 120 within each cylinder mechanically actuated valves normally closing all of said ports, and means including cams mounted directly on the crank shaft of the engine for unseating all of said valves.

4. In an internal combustion engine, a pair of cylinders, each having a two diameter bore, the head portion of the smaller bore of each cylinder having a lateral pock- 130

et, a pair of ports in each pocket, a gaseous fuel inlet port communicating with the upper portion of the larger bore in each cylinder, a two diameter piston arranged for operation within each cylinder, a crank shaft having two cranks to which the two pistons are respectively connected mechanically actuated valves normally closing all of said ports, and means including cams mounted directly on the crank shaft of the engine for unseating all of said valves. 50

5 10 15 20 25 30 35 40 45

5. In an internal combustion engine, a pair of cylinders, each having a two diameter bore, the head portion of the smaller bore of each cylinder having a lateral pocket, a pair of ports in each pocket, a gaseous fuel inlet ports communicating with the upper portion of the larger bore in each cylinder, a duct leading from the upper portion of the larger bore in each cylinder to the pocket at the head end of the other cylinder, a two diameter piston arranged for operation within each cylinder mechanically actuated valves normally closing all of said ports, and means including cams mounted directly on the crank shaft of the engine for unseating all of said valves. 60

15 20 25 30 35 40 45

6. In an internal combustion engine, a pair of cylinders, each having a two diameter bore, the head portion of the smaller bore of each cylinder having a lateral pocket, a pair of ports in each pocket, a gaseous fuel inlet port communicating with the upper portion of the larger bore in each cylinder, a duct leading from the upper portion of the larger bore in each cylinder to the pocket at the head end of the other cylinder, a two diameter piston arranged for operation within each cylinder, a crank shaft having two cranks to which the two pistons are respectively connected mechanically actuated valves normally closing all of said ports, and means including cams mounted on said crank shaft for unseating all of said valves. 70

15 20 25 30 35 40 45

7. An internal combustion engine having a pair of cylinders disposed in V-arrangement, each cylinder having a two diameter bore, a pocket extending laterally from the head end of the smaller chamber in each cylinder, each pocket having a pair of ports, a duct leading from the chamber of larger diameter in each cylinder to the pocket of the other cylinder, a gaseous fuel inlet duct leading into the larger chamber in each cylinder mechanically actuated valves normally closing all of said ports, and means including cams mounted directly on the crank shaft of the engine for unseating all of said valves. 75

15 20 25 30 35 40 45

from the head end of the smaller chamber in each cylinder, each pocket having a pair of ports, a duct leading from the chamber of larger diameter in each cylinder to the pocket of the other cylinder, a gaseous fuel inlet duct leading into the larger chamber in each cylinder mechanically actuated valves normally closing all of said ports, and means including cams mounted directly on the crank shaft of the engine for unseating all of said valves. 80

15 20 25 30 35 40 45

8. An internal combustion engine having a pair of cylinders disposed in V-arrangement, each cylinder having a two diameter bore, a pocket extending laterally from the head end of the smaller chamber in each cylinder, each pocket having a pair of ports, a duct leading from the chamber of larger diameter in each cylinder to the pocket of the other cylinder, a gaseous fuel inlet duct leading into the larger chamber in each cylinder, a two diameter piston arranged for operation within each cylinder mechanically actuated valves normally closing all of said ports, and means including cams mounted directly on the crank shaft of the engine for unseating all of said valves. 85

15 20 25 30 35 40 45

9. An internal combustion engine having a pair of cylinders disposed in V-arrangement, each cylinder having a two diameter bore, a pocket extending laterally from the head end of the smaller chamber in each cylinder, each pocket having a pair of ports, a duct leading from the chamber of larger diameter in each cylinder to the pocket of the other cylinder, a gaseous fuel inlet duct leading into the larger chamber in each cylinder, a two diameter piston arranged for operation within each cylinder, a crank shaft having two cranks to which the two pistons are respectively connected mechanically actuated valves normally closing all of said ports, and means including cams mounted directly on the crank shaft of the engine for unseating all of said valves. 90

15 20 25 30 35 40 45

In testimony whereof I affix my signature.

EVERETT R. BURTNELL.
